TOY HELICOPTER

Jack Rosenthal, South London, England, assignor to
Rovex Industries, Ltd., Merton, London, England, a
Corporation of Great Britain

Filed Dec. 29, 1969, Ser. No. 20,683

Term of patent 3½ years

Int. Cl. D21—02

U.S. Cl. D34—15

FIG. 1 is a side elevational view showing the design of a toy helicopter according to the invention;

FIG. 2 is a top plan view;

FIG. 3 is a bottom plan view;

FIG. 4 is a front elevational view; and

FIG. 5 is a rear elevational view.

I claim:

The ornamental design for a toy helicopter, substantially as shown.
